HEATING DEVICE FOR MOLTEN MATERIALS

Robert L. Nall, New Orleans, La., assignor to The Patent and Licensing Corporation, New York, N. Y., a corporation of Massachusetts

Application February 12, 1948, Serial No. 7,812

4 Claims. (Cl. 126—343.5)

1

This invention relates to a device for heating liquid materials. Although not confined thereto, the invention is particularly concerned with a device which is adapted for use as a superheater for heating liquefied bitumens, such as asphalt, to relatively high temperatures.

In the manufacture of asphalt-impregnated floor coverings and roofing materials such as roll roofing, shingles and the like, a continuous web or foundation sheet of fibrous felt is saturated by immersion in a bath of molten asphalt. When the impregnated web is to be used for the preparation of roof coverings, it is further processed to provide the web with a coating of relatively high melting point asphalt and a weather surface of mineral particles embedded in the coating. In the course of the saturation step the felt web is guided through a bath of molten saturant by passing the web over upper and lower sets of guide rolls, the lower set being submerged in the saturant adjacent the bottom of the saturator tank. In order to obtain rapid and effective saturation of the web, the asphalt saturant in the tank is maintained at a relatively high temperature, i. e., 450 to 525° F. The felt web being continuously introduced into the hot molten asphalt, however, has a marked cooling effect on the saturant and, of course, the continuous absorption of asphalt from the saturator bath by the web consistently depletes the supply of saturant. It is accordingly necessary to provide heating means which will continuously and rapidly reheat the cooled asphalt to the desired elevated temperature and which will also heat the make-up asphalt added to the saturator system.

Heating units which are commonly used in roofing plants for maintaining the saturant at elevated temperatures are tube-type refractory heaters wherein the asphalt is pumped through a tube positioned in a heated chamber. Such heating units have the disadvantage of being comparatively large and requiring extensive floor areas to accommodate them. Further, the refractory brick work involved in the construction of such heaters places a heavy weight upon the foundation and cracking of the brick due to settling is frequently encountered.

It is an object of this invention to provide an improved heating device adapted to heat molten liquids continuously and efficiently to relatively high temperatures and which requires a minimum of floor space, is relatively light upon its foundation and is not susceptible to injury from normal settling.

It is a further object of the invention to pro-

2

vide a heating device of the character indicated which is adapted to be used in conjunction with the saturator unit of a roofing machine to maintain the saturant therein at a temperature of 450 to 525° F.

Other objects and advantages of the invention will be apparent from the detailed description which is to follow and from the drawings in which,

Fig. 1 is a diagrammatic view of a heater constructed according to the invention showing the manner in which it may be associated with a felt saturator and with a make-up asphalt supply;

Fig. 2 is a view in elevation of the heater with a portion thereof broken away to show the arrangement of the flues;

Fig. 3 is a horizontal section taken along the line 3—3 of Fig. 2;

Fig. 4 is a sectional view along the line 4—4 of Fig. 3 showing the arrangement of baffles; and

Fig. 5 is a sectional view showing the method of securing the flues to the supporting structures.

Referring to the drawings, the numeral 10 designates generally a tank which forms the body or

25 casing of the heater and which comprises a cylindrical wall 12 provided with heads formed by hemispherical walls 14 and 15 secured as by welding to the upper and lower ends, respectively, of wall 12. A supporting structure for the tank 10 is provided by a girder 17 secured to the outer side of wall 12 and vertical columns 18 jointed to girder 17. Flanged inlet nozzles 22 and 23 are provided in hemispherical wall 15 and cylindrical wall 12, respectively, and a flanged outlet nozzle 24 is provided in hemispherical wall 14. In

30 order to prevent surging of the liquid being heated as it is pumped through the heater, the tank 10 is provided with baffles 25 and 26 which extend inwardly adjacent inlet 22 and outlet 24, respectively, each baffle being formed by two outwardly diverging perforated plates and a horizontal perforated circular plate secured to the outer ends thereof, as shown in Fig. 2. To permit access to the interior of tank 10, covered manholes 27 and 28 are formed in wall 14, and

35 covered manholes 29 and 30 are provided in wall 12 and wall 15, respectively.

The liquid, e. g. asphalt, as it passes upwardly 40 through the tank 10 is heated by direct contact with a series of parallel, horizontally-disposed sinuous flues through which hot combustion gases are passed. These flues in the embodiment illustrated are arranged in three banks of four flues each, the flues in the upper, intermediate 45 and lower banks being designated 32, 34 and 36,

respectively. It is a feature of the invention that each flue has an independent source of heat and that each flue passes through the tank 10 in the same plane and substantially in a plane parallel to the planes of the other flues. The ends of the flues 32 are provided with flanges 38 and 39, the flanges 38 being bolted to flanged ends 41 of flue outlets 42, which are secured as by welding in suitable openings in wall 12, and flanges 39 being bolted to flanged ends 44 of flue inlets 45, also secured in openings in wall 12. Flues 34 and 36 are similarly attached to flue outlets 50 and 52, respectively, and flue inlets 54 and 56, respectively. Parallel angle irons 58 and 59 which extend across the interior of tank 10 support the flues 32, 34 and 36 which are secured to the angle irons by U-bolts 60.

Hot combustion gases are received in the flues 32 from burners 62, an individual burner being positioned adjacent each flue inlet 45. Similarly, each of the flues 34 and 36 is heated by gases from burners 64 and 66, respectively, positioned adjacent each flue inlet 54 and 56, respectively. The burners 62, 64 and 66 are not per se a part of the invention and may be any suitable gas or oil-fired burner or the like. The combustion gases as they are discharged from the flues enter stacks which vent the gases to the atmosphere, an independent stack being provided for each bank of flues. The gases leaving flues 32 pass through flue outlets 42 into a stack 70 and the gases in flues 34 and 36 are vented through stacks 71 and 72, respectively. Additional stacks may be provided, if desired, as for example, an individual stack for each flue. A forced draft is induced in the banks of flues by suitable blowers 70a, 71a and 72a positioned in stacks 70, 71 and 72, respectively.

It will be observed that each of the three banks of flues is slightly offset horizontally with respect to the other two banks. This arrangement of the flues insures more intimate contact of the liquid with the flues as it progresses upwardly through the tank 10. Externally of tank 10, the banks of flue inlets and flue outlets are, of course, similarly offset with respect to one another.

Referring particularly to Figs. 3 and 4, it will be observed that two oblique baffles are provided to direct the liquid onto the flues in that portion of the tank where the flues are furthest from the wall 12. A baffle 75, having a flange 76 which is bolted to the inner side of wall 11, is positioned just below the upper bank of flues 32 and a baffle 77 having a flange 78 is similarly placed just below flues 34.

Referring particularly to Fig. 1, the numeral 80 designates a saturator unit in which is maintained a pool of liquid asphalt 82 through which a web 83 is guided in the usual manner by upper rollers 85 and lower rollers 86. The asphalt in the saturator 80 is returned to tank 10 to be reheated through a pipe 88 which extends from the lower part of the saturator 80 to inlet 23, the asphalt being pumped through the pipe by a positive pressure pump 89. A pipe 90 connected to outlet 24 conducts the heated asphalt back to saturator 80 after it has passed through the tank 10 and has been heated by the flues therein. An asphalt supply tank 92 which furnishes molten make-up asphalt to replace the asphalt absorbed by the web passing through the saturator is connected to inlet 22 by a pipe 94 which is provided with a positive pressure pump 93. The asphalt from make-up tank 92

may be continuously or intermittently pumped into tank 10.

An asphalt heating and circulating system is thus provided in which the heating device of the invention continuously heats the cooled asphalt from the saturator and at the same time heats the make-up asphalt as it is supplied to the system. In operating the heater, one or more banks of flues may be fired, depending upon the amount of heat to be supplied to the liquid being pumped through the heater. When heavy grades of felt are being saturated, for example, the temperature drop caused by the cooling effect of the felt is greater than that caused by a light weight felt, and accordingly, all three banks must generally be fired, particularly when the felt is being run through the saturator at a high rate of speed. When a light weight felt is being saturated, firing of a single bank may be sufficient to keep the asphalt at the desired temperature. Since each flue is fired by an independent burner it will be apparent that the heater of the invention has great flexibility and may be utilized to accommodate a large variety of operating conditions. When the heater is in operation, the tank 10 is filled with liquid and the flues are, therefore, submerged at all times whereby efficient heating is promoted.

While the drawings and the foregoing description of one embodiment of the invention relate to a heater having a vertical casing, the device of the invention may also be effectively embodied in a horizontal casing. It will be apparent that various other changes may be made without departing from the scope of the invention as defined in the appended claims and it is therefore intended that the foregoing shall be interpreted in an illustrative and not in a limiting sense.

I claim:

1. A device for continuously heating molten asphalt and the like to temperatures of the order of 450° F. to 525° F., comprising a tank adapted for continuous upward passage therethrough of the molten material to be heated, and a plurality of individually-fired, sinuous heating flues horizontally disposed in said tank in substantially parallel vertically-spaced relationship, the said flues being arranged in at least two vertically-spaced banks, the flues of one bank being horizontally offset with respect to the flues of the adjacent bank, and each of said flues being arranged to extend over a substantial portion of the internal horizontal cross-sectional area of said tank whereby to permit intimate contact between the exterior surface of the flues and the molten material passing upwardly through said tank.

2. A device for continuously heating molten asphalt and the like to temperatures of the order of 450° F. to 525° F., comprising a tank adapted for continuous upward passage therethrough of the molten material to be heated, a plurality of individually-fired, sinuous heating flues horizontally disposed in said tank in substantially parallel vertically-spaced relationship, the said flues being arranged in at least two vertically-spaced banks, and a stack adjacent each bank of flues adapted to receive the exit gases therefrom, each of said flues being arranged to extend over a substantial portion of the internal horizontal cross-sectional area of said tank whereby to permit intimate contact between the exterior surface of the flues and the molten material passing upwardly through said tank.

3. A device for continuously heating molten

asphalt and the like to temperatures of the order of 450° F. to 525° F., comprising a vertical tank adapted for continuous upward passage therethrough of the molten material to be heated, an inlet for the liquid in the lower portion of said tank, an outlet for the liquid in the upper portion of said tank, a plurality of individually-fired, sinuous heating flues horizontally disposed in said tank in substantially parallel vertically-spaced relationship, the said flues being arranged in at least two vertically-spaced banks, the flues of one bank being horizontally offset with respect to the flues of the adjacent bank, and each of said flues being arranged to extend over a substantial portion of the internal horizontal cross-sectional area of said tank whereby to permit intimate contact between the exterior surface of the flues and the molten material passing upwardly through said tank.

4. A device for continuously heating molten asphalt and the like to temperatures of the order of 450° F. to 525° F., comprising a vertical tank adapted for continuous upward passage therethrough of the molten material to be heated, an inlet for the liquid in the lower portion of said tank, an outlet for the liquid in the upper portion of said tank, a plurality of individually-fired, sinuous heating flues horizontally disposed in said tank in substantially parallel vertically-spaced relationship, the said flues being arranged in at least two vertically-spaced banks, the flues of one bank being horizontally offset with respect to the flues of the adjacent bank, and a stack
